UNITED STATES PATENT OFFICE.

EDWARD H. MOYLE, OF LOS ANGELES, CALIFORNIA.

DESIGN FOR A FRAME FOR CRUSHERS.

45,430.

Specification for Design.

Patented Mar. 17, 1914.

Application filed December 23, 1913. Serial No. 808,503. Term of patent 14 years.

To all whom it may concern:

Be it known that I, EDWARD H. MOYLE, a citizen of the United States, residing at Los Angeles, in the county of Los Angeles and State of California, have invented a certain new, original, and ornamental Design for a Frame for Crushers, of which the following is a specification, reference being had to the accompanying drawing, forming part thereof.

The figure is a perspective view, showing my new design.

I claim:

The ornamental design for a frame for crushers, as shown.

EDWARD H. MOYLE.

Witnesses:

N. L. PERRY,
F. GAIL EWING.
